UNITED STATES PATENT OFFICE.

AMOR W. DOUGLAS, OF ALBUQUERQUE, TERRITORY OF NEW MEXICO.

MULTIPLEX TELEGRAPH SYSTEM.

No. 895,350.

Specification of Letters Patent.

Patented Aug. 4, 1908.

Application filed April 13, 1907. Serial No. 368,003.

To all whom it may concern:

Be it known that I, AMOR W. DOUGLAS, a citizen of the United States, residing at Albuquerque, in the county of Bernalillo and Territory of New Mexico, have invented new and useful Improvements in Multiplex Telegraph Systems, of which the following is a specification.

This invention relates to multiplex telegraph systems of that type in which sending and receiving signaling apparatus responsive to alternating current are employed in connection with a simple "Morse" system.

The invention has for one of its objects to improve and simplify the construction and operation of telegraph systems of this character so as to be comparatively easy and inexpensive to manufacture and keep in repair, thoroughly reliable and efficient in use, and readily manipulated.

A further object of the invention is the provision of a multiplex telegraph system in which the source of alternating current is located only at the main or central office, thus obviating the necessity of skilled attendants, not only at the main station, but at the distant or secondary stations of the system according to other multiplex systems employing alternating currents for transmitting messages.

A still further object of the invention is the provision of secondary or sub-station sending and receiving sets which are extremely simple in organization so that they can be manipulated by operators of average intelligence, it being necessary merely to cut the sets into the line wires when it is desired to transmit a larger number of messages than is possible by the Morse sets as at busy times and to cut the alternating current sets out of service during less busy times.

Another object is to employ a single source of alternating current for supplying a plurality of line wires in which are included the continuous and alternating current sets, the organization of the system being such that the inductive effect of current in one line is minimized as regards the other or others and the alternating current source or generator is connected in multiple relation with the several line wires through independent transformers.

With these objects in view and others, as will appear as the description proceeds, the invention comprises the various novel fea-

tures of construction and arrangement of parts which will be more fully described hereinafter and set forth with particularity in the claims appended hereto.

In the accompanying drawing, which illustrates one of the embodiments of the invention, the figure is a diagram of the circuits of the system.

Referring to the drawing, *m* and *m'* designate respectively the two line wires extending from the main office of the system designated generally by *M* to distant way offices *O* and *O'* and secondary stations *A* and *B*. At the main station *M* are Morse sets *N* and *N'* connected respectively with the line wires *m* and *m'* and continuous or uni-directional current is supplied for signaling by the Morse sets *N* and *N'*, and *O* and *O'* from a battery *b* or generator by the conductors 1 and 2. The Morse sets at the main and way stations are of the usual character, as will be readily understood, and the ends of the line wires opposite from the source of continuous current will be connected to a battery or generator and to ground for the return currents to pass back to the battery *b* through the earth. Bridging each set at the way stations *O* and *O'* is a condenser *c* forming a shunt around the said sets for the alternating currents passing through the line wires.

In the line wires are choke coils *I* and *I'* at the main station or office and *I²* and *I³* at the secondary offices *A* and *B*, respectively, and for short circuiting these coils, switches *S* are employed.

At the main station or office *M* is an alternating current generator *AC* that has one of its brushes connected by the branch conductor 3 with the primary coils *p* of transformers *T* and *T'* and the opposite sides of the primary coils are connected with the other brush of the generator by conductors 4 and 5 respectively, that include the armatures *a'* and *a''* of sounders *s'* and *s''* controlled by the keys *K* and *K'* which are normally closed. The secondary coils *s* of the main transformers are connected in series with the line wires, so that when the primary circuits are closed by the keys *K* and *K'*, each line wire will have impressed thereon an alternating electromotor force which is used for transmitting messages between the alternating current sets of the main station or office *M* and the secondary offices *A* and *B*.

Although the secondary stations or offices are not shown equipped with ordinary Morse sets, it is to be understood that they are employed in actual practice in conjunction with the alternating signaling sets. At the main office are arranged a plurality of sending and receiving sets C and D which, in organization, are like the sets at the offices A and B and the circuits of the sets A and C are inductively related to the line wire m' by transformers t and t' respectively, while the sets B and D are inductively related to the line wire m by transformers t^2 and t^3 respectively. Each circuit of the sets A, B etc., includes a relay r bridged by a condenser c' and whose armature a controls the local circuit of a repeating sounder b' which in turn controls the local circuit of a reading sounder d . Associated with each alternating current signaling set, both at the main and secondary offices, is a conductor 8 including a variable resistance R and a condenser c^2 which may be adjustable, each conductor 8 at the main station being connected to ground at 6 through the armature of sounders o and o' . The sounders s' and o , and s'' and o' , are each in a local circuit including a battery e , the key K controlling one circuit and the key K' , the other. The primary coil of each alternating current signaling set and the circuit thereof including the relay and adjustable condenser forms a static circuit and normally the armature of the relay is held by its spring in a position to maintain the local circuit of the repeating sounder or relay b' closed. In the present diagram, the key K is shown closed and the key K' open, while the keys k and k' are in closed position.

When the business on the system is such that it can be conveniently handled by the Morse sets, the alternating current signaling sets are cut out of service and the switches S may be closed. In sending messages, the current passes from the battery b to either or both lines through the switches S , sounding relays and keys of the Morse sets included in the lines. When, however, the alternating current signaling sets are connected in circuit, the switches S are opened and the continuous current passes through the induction coils in the lines m and m' during the signaling by the Morse sets. Any number of way offices may be provided and the continuous current, after passing through the sets at these stations, returns by way of the earth to the battery in the usual manner.

When it is desired to bring the alternating current signaling set at the station A or B into service for handling an accumulation of business, the operator communicates the fact from such station to the operator at the main station by means of the Morse instruments and the main operator instructs the secondary station operator to cut his signaling set into service, it being understood that

the secondary coils of the transformers t and t' are provided with double plugs at the ends nearest to the main office that are adapted to be plugged into jacks suitably arranged, while the conductors 8 are provided with double plugs adapted to be plugged into jacks at the ends of the secondary coils farthest from the main station, as will be readily understood. Then by operating the key k or k' , a message can be transmitted to the set C or D at the main office.

Assuming that a message is to be sent from the set C to the sub-station set A, the key K' is opened so as to open the circuit in which the primary of the transformer T' is included and also the circuit including the conductor 8, resistance R and condenser c^2 associated with the set C. No alternating current, therefore, is generated in the line wires m' and consequently the relays r of the sets C and A lose their magnetism and the armatures a are pulled by the retractile springs against the contacts of the relay or repeating sounder circuits, which sounders in turn open the local circuits of the reading sounders d . Thus, by manipulating the key K' , the circuits are opened and closed so that the reading sounders are actuated for signaling purposes, as will be readily understood.

When one of the sub-station operators sends a message to the central station, the key k' is opened, whereby the non-inductive resistance R of the set being employed is included in the static circuit comprising ground 9, conductor 8, the key thereof, condenser c^2 , line wire and secondaries of the transformers therein, conductor 8 of the set at the main station connected with said line wire, non-inductive resistance and condenser included in the wire, the controlling armatures of sounders o or o' , and by way of ground to the ground 9. The resistance included in the circuit reduces the alternating current being set up in the main line wire by the generator AC to such an extent that the force of the retractile spring of the relays overcomes the weakened attractive force so that the local circuits of the repeating sounders open. Thus, by operating the key k or k' , the operator at either of the sub-stations can signal to the operator at the main set connected with the sub-station. When any one of the line wires is operating with alternating current, the inductive effect thereof is diminished to a minimum as regards the other idle line wire or wires through the medium of the induction coils included in the line wires, as will be readily understood.

From the foregoing description, taken in connection with the accompanying drawing, the advantages of the construction and of the method of operation will be readily apparent to those skilled in the art to which

the invention appertains, and while I have described the principle of operation of the invention, together with the apparatus which I now consider to be the best embodiment thereof, I desire to have it understood that the apparatus shown is merely illustrative and that such changes may be made when desired as are within the scope of the claims.

10 Having thus described the invention, what I claim is:

1. In a telegraph system, the combination of a line wire, a circuit including a source of alternating current, a transformer connecting the circuit with the line wire, a grounded wire including resistance and capacity, a local circuit including a battery, means for opening and closing the local circuit, and devices controlled by the said means for opening and closing the source-including circuit and also the grounded conductor.

2. In a telegraph system, the combination of a line wire, a circuit including a source of alternating current, a transformer connecting the circuit with the line wire, a grounded wire including resistance and capacity, a local circuit including a battery, means for opening and closing the local circuit, devices controlled by the said means for opening and closing the source-including circuit and also the grounded conductor, a main station signaling set at the said source and inductively connected with the line wire, a secondary station signaling set inductively connected with the wire, a grounded conductor at the secondary station set, and means for varying the conductivity through the last-mentioned conductor without opening the path of current through the same for signaling from the secondary to the main station.

3. In a telegraph system, the combination of a line wire, a circuit including a source of alternating current, a main station signaling set inductively connected with the line wire, a grounded conductor, a secondary signaling set, means for opening the grounded conductor when signaling from the main to the secondary station, a grounded conductor at the secondary station, and means for varying the conductivity of the second conductor without interrupting the same for signaling from the secondary to the main station.

4. In a multiplex telegraph system, the combination of a line wire, continuous current signaling devices connected therewith, a source of continuous current, means for connecting the said source with the line wire, transformers in the line wire, a circuit connected with one of the transformers and including a source of alternating current, main and secondary signaling sets connected with the line wire, a conductor connected with the line wire to form a path for current when signaling from the secondary to the main station, means for interrupting the con-

ductor and for opening the source-including circuit, and a key-including conductor connected with the line wire at the secondary set.

5. The combination of a plurality of line wires, continuous current signaling devices connected therewith, a common source of continuous current adapted to be thrown into or out of circuit with the line wires, a main station signaling set connected with each line wire, a secondary station signaling set connected with each line wire, a single alternating current generator, multiple circuits inductively connecting the line wires with the generator, a grounded conductor connected with each line wire at each main and secondary station set, independent local circuits for the main station sets and including a source of current and a key, and means controlled by the local circuit for simultaneously opening the generator circuit and one of the grounded conductors.

6. In a telegraph system, a plurality of line wires including continuous current signaling sets, alternating current signaling sets operatively related to the line wires, a common source of current for all of the alternating current sets, choke coils included in the line wires, short circuiting means for the coils, and a source of continuous current connected with the line wires and supplying the latter through the said means.

7. In a telegraph system, the combination of a line wire, a grounded conductor connected therewith and including resistance and capacity, a signaling set inductively related to the line wire, a source of alternating current, a circuit inductively relating the source to the line wire, a local circuit including a source of current, a key for opening and closing the circuit, an electro-magnet in the local circuit having its armature contained in the alternating current circuit for opening and closing the same, and a second electro-magnet in the local circuit and arranged with its armature to interrupt the path of current through the conductor.

8. In a telegraph system, a line wire, continuous current signaling apparatus connected therewith, signaling sets responsive to intermittent current impulses, means for inductively relating the sets to the line wire, a source of intermittent current impulses, a path including resistance and capacity leading from the line wire to ground at each set, and a means for making and breaking the circuit of the said source and simultaneously opening and closing the said path of one of the sets.

9. In a telegraph system, a line wire, a plurality of signaling sets responsive to alternating current, transformers inductively relating the sets to the line wires, a plurality of continuous current signaling apparatus, a source of alternating current, a transformer inductively relating the source to the line

wire, means for opening and closing the circuit of the source, a conductor at each set connected with the line, an adjustable resistance in each conductor, a condenser associated with said resistance, and means for making and breaking the circuit through each conductor at the same time the current of the said source is interrupted.

10. In a telegraph system, a line wire, continuous current signaling apparatus connected therewith, a source of continuous current, induction coils connected in the line, short circuiting switches for the coils, an alternating current circuit, a transformer inductively relating the circuit to the line, a plurality of signaling apparatus containing circuits, transformers inductively relating the said line to the last-mentioned circuits, a conductor associated with the signaling circuits and including capacity and resistance, and a key controlling the alternating current circuit and the said conductors.

11. In a telegraph system, a line wire, continuous current signaling apparatus connected therewith, an alternating current circuit, a transformer inductively relating the circuit to the wire, a plurality of circuits containing signaling devices, transformers inductively relating the line with the last-mentioned circuits, a conductor in each of the last-mentioned circuits connected with the line

wire and adapted to be connected to ground, capacity and resistance devices included in each conductor, and a key for making and breaking the alternating current circuit and for grounding or ungrounding one of the said conductors.

12. In a multiplex telegraph system, a plurality of line wires, a central station, way and secondary stations, grounded conductors connected with the line wires at the stations, continuous current signaling apparatus connected with the line wires at the central and other stations, a plurality of circuits at the main and secondary stations each including signaling devices, a source of alternating current at the main station, transformers inductively relating the circuits of the source with the line wires, means for breaking the continuity of the alternating current and for opening one of the grounded conductors to signal from the main to a secondary station, and means for varying the current intensity for signaling from a secondary to the main station.

In testimony whereof, I affix my signature in presence of two witnesses,

AMOR W. DOUGLAS.
